[57]

ABSTRACT

A conveyor screw is mounted in a working chamber to convey a fluid material, and is sealed by a row or stack of sealing elements extending along a surface line of the conveyor screw perpendicular to the turns of the same.

SEALED CONVEYING APPARATUS

BACKGROUND OF THE INVENTION

In accordance with the prior art, a conveyor screw rotor is arranged in a stator consisting of an elastic material, such as rubber. Due to the kneading of the rubber stator during the rotation of the conveyor screw, the material of the stator is soon worn. Furthermore, elastomers which may be used for the stator, are very sensitive to a chemical action by the transported medium so that conveyor screw pumps according to the prior art are not suitable for transporting and pumping many fluid materials.

It is one object of the invention to overcome this disadvantage of the prior art, and to provide a conveyor screw apparatus which can be comparatively easily manufactured, is resistant against wear and corrosion, and suitable for conveying all kinds of fluid.

With these objects in view, a row of platelike sealing elements made of a rigid material, such as metal or a synthetic plastic material, is arranged along a surface line of the conveyor screw along the length of the same. Preferably, the surface line extends perpendicular to the turns of the conveyor screw. The sealing elements abut with their inner end faces on the surface of the conveyor screw, and are urged by pressure means into sealing abutment with the same. The sealing elements obtain a complete sealing of the worm screw without requiring a high abutment pressure. Any kind of material which has low friction and thereby small wear, and which is inert to conveyed medium, may be used for the sealing elements.

The pressure means by which the outer ends of the sealing elements are biased toward the surface of the worm screw, may be a pressure chamber with a pressure fluid in the same acting on the outer ends of the sealing elements. The pressure chamber may be formed by the pressure outlet means of the apparatus, but may be a separate pressure chamber receiving a fluid medium from the pressure outlet means, and having dimensions permitting a circulation of the pressure medium within the pressure chamber. However, the pressure means may be provided in the form of springs acting on the outer ends of the sealing elements. The mechanical spring construction is advantageous, if the apparatus is not used for conveying a liquid medium, but for comparatively fluid solid material, such as vegetables or fruit. It is also possible to provide springs in a pressure chamber in which a fluid medium acts on the outer ends of the sealing elements in addition to the spring action. While it is preferred to provide the pressure chamber with the conveyed material if the same is sufficiently liquid, a separate pressure fluid is supplied to the pressure chamber if a fluid solid material is conveyed.

It is advantageous to use a smaller sealing element in the region of the pressure outlet, and thicker sealing element in the region of the suction inlet so that the sealing effect is increased in the high pressure region of the output.

It is also advantageous to divide the pressure chamber and to supply fluid at a lower pressure to a pressure chamber portion in the region of the inlet, than to a pressure chamber portion in the region of the outlet of the apparatus so that the sealing pressure conforms to the pressure of the conveyed material in the respective sealing region. In this manner, unnecessarily high pressure, and consequent abrasion and high friction, can be avoided.

The sealing effect is improved when the inner ends of the sealing elements are shaped to conform to the contour of the surface of the worm screw on which they abut. Two parallel rows of staggered sealing elements are advantageously used to improve the sealing effect.

The conveyor screw may have a continuous helical surface, but it is advantageous to construct the conveyor screw of a series of adjacent discs angularly staggered and eccentric to the axis of the rotor, and having peripheral annular surface portions which together form the outer surface of the conveyor screw. The annular peripheral surface portions of the discs are

parallel to the axis, so that the inner ends of the sealing elements, which slide on the annular peripheral surface portions, obtain perfect sealing contact. Preferably, the peripheral surface portions of the discs are not circular, but have an outermost part whose radius of curvature conforms the radius of the inner surface of the working chamber in which the conveyor screw rotates so that the wear is reduced, in accordance with the invention. In another construction according to the invention, the helical turns of the conveyor screw and the cooperating inner ends of the sealing elements have a trapezoidal shape so that a particularly good sealing is obtained.

The sealed conveying apparatus according to the invention is suited for conveying all kinds of fluid material. For example, delicate fruits or nuts, beans and granular material can be conveyed.

5 The apparatus is also particularly suited as a pump which obtains comparatively high pressure in the range of 60 to 80 at. The apparatus of the invention is also suitable for conveying a mixture of a liquid with solid material, such as preserved fruit in syrup, mortar and also cement, as long as the

10 same is still liquid.

15 It has been shown by test that comparatively high pressures in the range of between 60 and 80 at. can be obtained when liquids, such as oil are conveyed. Around the conveyor screw, substantially the same pressure prevails so that the loads on the bearings, the bending deflection of the conveyor screw and its shaft, the stress on the rotor, and the wear of the housing and the rotor, are low.

20 When it is required to transport great quantities of material, the present invention provides two conveyor screw rotors which are driven at the same rotary speed in parallel positions at a substantially constant radial distance of the confronting conveyor screw surfaces. Two corresponding working chambers are provided in the housing and receive the conveyor

25 screws in sliding contact. The sealing elements are disposed in the plane where the distance between the conveyor screws is the smallest. The inlets for the two conveyor screws are advantageously arranged at the regions where the surfaces of the two conveyor screws have the greatest distance from each other.

30 In one embodiment of the invention, the two ends of each sealing element respectively abut the two conveyor screws in sliding and sealing abutment so that each conveyor screw performs the function of a pressure means acting on the sealing elements. In such an arrangement, the sealing elements

35 are reciprocated by the two conveyor screws.

35 Preferably, the sealing elements are simultaneously biased toward the respective conveyor screws, so that the sealing contact is maintained after wear. An elastic piece or a compression spring may be provided in the reciprocating sealing elements, and pretensioned by the two conveyor screws so that the sealing contact is maintained when the material is worn off or corroded. It is also possible to provide each conveyor screw with a row of sealing elements whose other ends are located in the pressure chamber in which a pressure fluid

40 acts on the ends of the sealing elements to urge the same in opposite direction into engagement with the respective conveyor screws.

45 In a modified embodiment, the rotor has two oppositely wound conveyor screws whose remote ends receive the fluid material from a pair of inlets, while the adjacent ends of the conveyor screws transport the material to an outlet means located between the same. In this manner, axial forces along the rotor are compensated, which is advantageous for a perfect cooperation of the conveyor screws with the corresponding sealing elements whose relative movement is facilitated.

50 It is advantageous to make adjacent sealing elements of different materials which slide on each other with little friction. For example, alternate sealing elements of the row may consist of plastic synthetic material, such as Teflon, and steel. Such an arrangement not only reduces the friction during the relative movement of the sealing elements, but the metal elements conduct the developed friction heat away and dissipate the same, which cannot be accomplished to the same degree by synthetic materials. On the other hand, the sealing ele-

55 ments are reciprocated by the two conveyor screws.

60 In a modified embodiment, the rotor has two oppositely wound conveyor screws whose remote ends receive the fluid material from a pair of inlets, while the adjacent ends of the conveyor screws transport the material to an outlet means located between the same. In this manner, axial forces along the rotor are compensated, which is advantageous for a perfect cooperation of the conveyor screws with the corresponding sealing elements whose relative movement is facilitated.

65 It is advantageous to make adjacent sealing elements of different materials which slide on each other with little friction. For example, alternate sealing elements of the row may consist of plastic synthetic material, such as Teflon, and steel. Such an arrangement not only reduces the friction during the relative movement of the sealing elements, but the metal elements conduct the developed friction heat away and dissipate the same, which cannot be accomplished to the same degree by synthetic materials. On the other hand, the sealing ele-

70 ments are reciprocated by the two conveyor screws.

75 It is advantageous to make adjacent sealing elements of different materials which slide on each other with little friction. For example, alternate sealing elements of the row may consist of plastic synthetic material, such as Teflon, and steel. Such an arrangement not only reduces the friction during the relative movement of the sealing elements, but the metal elements conduct the developed friction heat away and dissipate the same, which cannot be accomplished to the same degree by synthetic materials. On the other hand, the sealing ele-

ments consisting of synthetic material prevent the generation of a series of voltages along the row of sealing elements, which would increase corrosion.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawing.

BRIEF DESCRIPTION OF THE DRAWING

FIG. 1 is a side elevation, partially in longitudinal section, and illustrating a first embodiment of the invention;

FIG. 2 is a vertical cross section taken along line II—II in FIG. 1;

FIG. 3 is a side elevation, partially in longitudinal section, and illustrating a modified embodiment in which the pressure chamber is part of the outlet of the apparatus;

FIG. 4 is a side elevation, partially in longitudinal section, and illustrating a modification of the apparatus of FIG. 1 in which a closed pressure chamber communicates with the outlet;

FIG. 5 is a side elevation at a reduced scale illustrating an apparatus according to the invention;

FIG. 6 is a cross-sectional view taken along line VI—VI in FIG. 7;

FIG. 7 is a side elevation, partially in longitudinal section of a modified construction of the sealing elements;

FIG. 8 is a plan view of the embodiment of FIGS. 5 to 7, partially in horizontal section taken along line VIII—VIII in FIG. 7;

FIG. 9 is a side view, and FIG. 10 is a front view of a sealing element used in the embodiment of FIGS. 7 and 8;

FIGS. 11 to 15 illustrate an apparatus of the invention provided with a rotor constructed of discs wherein FIG. 11 is a side elevation, partially in longitudinal section, and taken on line XI—XI in FIG. 12;

FIG. 12 is a cross-sectional view taken on line XII—XII in FIG. 11;

FIG. 13 is a plan view, partially in horizontal section, taken on line XIII—XIII in FIG. 12;

FIG. 14 is a fragmentary side elevation, partially in vertical section, taken on line XIV—XIV in FIG. 15 and illustrating a modification on an enlarged scale;

FIG. 15 is a cross-sectional view taken on line XV—XV in FIG. 14;

FIG. 16 is a schematic end view of two staggered rows of sealing elements;

FIG. 17 is a fragmentary schematic, partially sectioned view, illustrating a conveyor screw with trapezoidal turns cooperating with correspondingly shaped sealing elements;

FIG. 18 is a fragmentary schematic view illustrating a detail of FIG. 17 on an enlarged scale;

FIG. 19 is a side elevation, partially in longitudinal section illustrating a row of sealing elements provided with a compensating end member in accordance with a modification of the invention;

FIG. 20 is a cross-sectional view taken on line XX—XX in FIG. 19;

FIG. 21 is a side elevation, partially in longitudinal section, illustrating a modification of the embodiment of FIG. 19, in which the rotor is provided with a plurality of conveyor screws;

FIG. 22 is a perspective view of a sealing element particularly adapted for a conveyor screw composed of discs;

FIG. 23 is a plan view, partially in section, illustrating a cooperation between the sealing elements and the conveyor screw discs in the embodiment of FIG. 21 and FIG. 19;

FIG. 24 is a side elevation, partially in longitudinal section, illustrating an embodiment of the invention provided with two parallel rotors;

FIG. 25 is a cross-sectional view taken on line XXV—XXV in FIG. 24;

FIG. 26 is a side elevation, partially in longitudinal section, illustrating a modified embodiment of the invention with two parallel rotors;

FIG. 27 is a cross-sectional view taken on line XXVII—XXVII in FIG. 26;

FIG. 28 is a fragmentary side elevation, partially in longitudinal section, illustrating a modification in which the sealing elements of two conveyor screws are biased by a pressure liquid;

FIG. 28a is a fragmentary sectional view illustrating a modification in which the sealing elements partly consist of resilient material;

FIG. 29 is a perspective view on an enlarged scale illustrating a sealing element used in the embodiment of FIG. 28a; and

FIG. 30 is a side elevation, partially in longitudinal section, and illustrating another embodiment of the invention.

DESCRIPTION OF THE PREFERRED EMBODIMENTS

Referring first to the embodiment of FIGS. 1 and 2, the apparatus has a housing 10 provided with a suction inlet 11 having a flange 11a and a pressure outlet 12 having a flange 12a.

A rotor shaft 13 has a portion 13a to which a motor shaft can be coupled, substantially as shown at 44 in FIG. 5 in which a motor 52 is connected with a housing 40.

Shaft 13 is mounted in ball bearing supported on a tubular housing part 14, and passes through an opening in a housing wall which is sealed by a stuffing box 19. The other end portion 13b of shaft 13 is mounted in a bearing 15 which is located in the liquid in the outlet 12. The rotor R has a conveyor screw 13c of circular cross section which is located in a substantially cylindrical working chamber 10a in contact with the inner surface of the same.

A row of sealing elements 16 is guided between a pair of guide walls 10b of housing 10 in a plane passing through the axis of rotor R. The inner ends of sealing elements 16 are in sliding contact with a surface line of conveyor screw 13c, and preferably have inner end faces whose curved contour matches the curvature of the conveyor screw 13.

Sealing elements 16 are movable in radial direction of the rotor, and perpendicularly to the longitudinal direction of the row of sealing elements 16 into a pressure chamber 17 into which pressure fluid 18 is supplied from the outlet 12 through a bore 9. The pressure chamber 17 is formed in a housing part 15 which comprises guide walls 10b, end walls in sliding engagement with the first and last sealing element 16, and a top wall connecting guide walls 10b.

The pressure medium K in the pressure chamber 17 acts on the outer ends of sealing elements 16 to bias the same into sealing abutment with the surface of conveyor screw 13c so that a fluid material 18 is transported from inlet 11 through working chamber 10a into outlet 12.

Due to the radial movement of the sealing elements, the fluid medium K in pressure chamber 17 is moved, and therefore it is advantageous to provide sufficient space in pressure chamber 17 above the outer ends of sealing elements 16 so that the pressure fluid K can circulate in the pressure chamber 17. As shown in FIG. 4, the height h of the pressure chamber should be sufficient to permit the circulation indicated by arrows P/1 in FIG. 4.

However, instead of increasing the height h of the pressure chamber 17, it is also possible to make the pressure chamber wider than the sealing elements 16, and such a construction will be described with reference to FIGS. 6 and 8.

Generally speaking, the cross section of the closed pressure chamber should permit circulation of the pressure fluid K so that the movement of the sealing elements is not inhibited. However, due to the fact that some sealing elements 16 move into the pressure chamber while others move out of the pressure chamber, the volume of the pressure fluid K is substantially constant, and leakage losses are compensated through the opening 9.

In the embodiment of FIG. 1, three groups of sealing elements 16a, 16b, and 16c are provided which are of different thickness. The thinner sealing element 16c in the high pressure region can follow the contour of conveyor screw more closely, and obtain the better sealing required at the high pressure side.

The thick sealing elements 16c on the inlet side provide a sufficient seal since the pressure in the inlet 11 is lower than in the outlet 18. The intermediate thickness of the sealing elements 16b corresponds to the intermediate pressure prevailing in this portion of the working chamber 10a.

In the embodiment of FIG. 3, the housing 20 has an outlet 28 communicating through a pressure chamber 27 with an outlet conduit 22 which is connected by the working chamber with the inlet 21. The rotor shaft 24 enters the housing through a stuffing box 29 and has an end portion supported in a bearing of housing 20. The conveyor screw 23 is located in a cylindrical working chamber, as will be described with reference to FIG. 10, and a housing part 25 has lateral guide walls for guiding the sealing elements 26 which are arranged in a row.

Since the fluid medium, or liquid, conveyed by conveyor screw 23 flows through the pressure chamber 27 at high pressure, the sealing elements 26 are biased into engagement with the inner faces thereof with the outer surface of the worm screw 23.

In the embodiment of FIG. 4, a housing 30 has an inlet 31 and an outlet 32. A rotor shaft 34 is mounted in the housing for rotation and has a conveyor screw 33 located in a cylindrical working chamber, as described with reference to FIG. 2. A row of sealing elements 36 is guided in housing part 35 for movement toward and away from the axis of rotor R and shaft 34. As in the embodiment of FIG. 1, the pressure chamber 37 is substantially closed and communicates through an opening 35a with the outlet 32 so that the liquid 18, which is under high pressure, flows in the direction of the arrow P/I into the pressure chamber and circulates in the same. The minimum distance *h*, the height of the pressure chamber 37, is the distance between the outermost ends of the sealing elements 36 and the top wall of housing part 35, and this height is selected so that the indicated circulation can take place.

Another embodiment is illustrated in FIGS. 5 to 8. A housing 40 has an inlet 41 and an outlet 42. The rotor R includes the rotor shaft 44 and a conveyor screw 43 which is located in a cylindrical working chamber, as best seen in FIG. 6. Motor 52 drives rotor shaft 44 through a coupling as shown in FIG. 5.

Two parallel rows of sealing elements 46a, 46b are guided between lateral walls of housing part 45 which contains the pressure chamber 47. The sealing elements 46a and 46b of the two rows are staggered, as best seen in FIG. 8 so that the spaces between adjacent sealing elements 46a are covered by corresponding sealing elements 46b of the other row which improves the sealing effect.

Pressure chamber 47 is divided by partitioning walls 53a and 53b into three chamber portions 47a, 47b, and 47c. Pressure chamber 47a communicates through a conduit 48a with a portion of housing 40 in which a somewhat higher pressure than the pressure at the inlet 18 prevails. The pressure chamber portion 47b communicates through a conduit 48b with a portion of the working chamber at which somewhat higher pressure prevails, and the pressure chamber portion 47c communicates through an inlet opening 50 with the pressure outlet 42 so that the highest pressure prevails in pressure chamber portion 47c. As a result of this arrangement, different pressures act on different groups of sealing elements, and the pressure is lowest in the region of the suction inlet, and highest in the region of the pressure outlet so that the sealing effect of the sealing elements is increased as the pressure along the conveyor screw 43 increases. A comparatively low sealing pressure prevails at the inlet end of the conveyor screw 43 so that high friction, which would be caused by high pressure in the region of the pressure chamber, is avoided. As a result, the power required for rotating the rotor, and the wear of the parts which are in sealing engagement, are reduced.

As best seen in FIG. 8, the rows of sealing elements 46a, 46b extend perpendicular to the direction of the turns of conveyor screw 43, and not in an axial plane. Consequently, the surface line along which the inner ends of the sealing elements are in contact with the surface of conveyor screw 43, is perpendicular to the direction of the turns, at an angle to the axis of rotor R, as clearly shown in FIG. 8. This arrangement permits it to shape the inner ends of the sealing elements to match the contour of the engaged surface portion of the worm screw, whereby the sealing effect is improved.

Perforated U-shaped stop members 51 are disposed in the pressure chamber portions 47a, 47b, 47c, and serve to limit the movement of the sealing elements when the same are in contact with the outermost surface portion of the conveyor screw 43. Stop members 51 prevent a separation of the sealing elements from the conveyor screw surface, which may occur at high speed. The perforation in stop members 51 permit the circulation of the liquid 18 in the pressure chamber portions 47a, 47b, 47c.

As shown in FIG. 6, the outermost part of the pressure chamber is widened as shown at 47d, and the stop members 51 have a corresponding width. Consequently, circulation of the liquid can take place within the U-shaped stop member 51 while the sealing elements reciprocate outward and inward in radial direction.

FIG. 9 illustrates a sealing element S in a position in which its inner end is on top. The inner ends, as shown in FIG. 7, are rounded to facilitate the riding of the inner ends of the sealing elements on the turns of the conveyor screw 43. As shown in FIG. 10, which shows the sealing element S in the position of FIG. 6, the inner end of the sealing elements are curved to follow the contour of the conveyor screw. By adapting the shape of the inner end to the shape and contour of the corresponding engaged conveyor screw portions, improved sealing is obtained.

In the constructions shown in FIGS. 11 to 15, the housing 60 has an inlet 61 and an outlet 62. A conveyor screw 63 and a shaft 64 form the rotor which is mounted in bearings of housing 60. A single pressure chamber 67 is formed by housing part 65, and contains the outer end of the sealing elements 66 whose inner ends are in sealing contact with the conveyor screw 63. Conveyor screw 63 is constructed in a different manner than in the above-described embodiments. The conveyor screw consists of discs 63₁ to 63₁₂, see FIG. 14, and the discs are angularly spaced equal angular distances in relation to the axis of the rotor, as best seen in FIGS. 12 and 15. The annular peripheral surface portions of the discs are parallel to the axis of the rotor, but not exactly circular since the portion D of each disc 63 which is in sliding contact with the cylindrical inner surface of the working chamber, is provided with the same radius of curvature as the cylindrical surface of the working chamber so that none of the discs is in line engagement with the inner surface I of the working chamber, but in full contact for a circumferential distance *a*, as shown in FIG. 15.

FIGS. 14 and 15 show that parts of the annular peripheral surfaces of adjacent discs 63 are aligned in axial direction, since each circumferential region D of one disc 63 overlaps the peripheral surface of the adjacent disc. However, the radius of curvature in the region D is not substantially different from the radius of the other circular peripheral surface of the disc, so that the inner end faces 66a, see FIG. 22, of the sealing elements 66, can be designed to match the circular peripheral portion of disc 63 with which they are in contact for longer periods than with the differently curved parts of the peripheral surface portions in the region D. In addition to the sealing of the conveyor screw 63 in circumferential direction obtained in this manner, good sealing in axial direction is also obtained, as best seen in FIGS. 13 and 14, each conveyor screw disc 63₁ to 63₁₂ being engaged by the inner end face 66a of a sealing element 66₁ to 66₁₂. A line engagement between sealing elements and the conveyor screw, is avoided, and surfaces are in sealing contact.

As particularly shown in FIGS. 13 to 15, housing part 65 forms the pressure chamber 67, and has intermediate wall means 65a with bores 65b which connect the pressure chamber 67 with spaces in which compression coil spring 71 are arranged, abutting at one end of wall means 65a and at the other end at a correlated sealing element 66. It is possible to omit the pressure chamber and the fluid in the same, and to bias the sealing elements 66 only by springs 71, which is particularly advantageous if the fluid material transported by the conveyor screw is unsuitable as pressure medium, which is the case when solid fluid material, such as beans or fruits, are transported.

As shown in FIG. 16, it is preferred to provide two adjacent parallel rows of sealing elements S_1 to S_2 which are staggered to each other to obtain a good sealing effect.

FIGS. 17 and 18 illustrate a modification in which a conveyor screw of rotor R has turns whose cross section is trapezoidal. The inner ends of the sealing elements S_1 , S_2 also have trapezoidal face portions to match the contour of the conveyor screw, as best seen in FIG. 17. Sealing elements 76 in FIGS. 17 and 18 are not arranged in two parallel rows as shown in FIG. 16, but alternate sealing elements S_1 and S_2 are staggered and overlap. The manufacture of a trapezoidal conveyor screw on rotor R is comparatively easy. Nevertheless, this construction obtains a very good seal, and a reliable operation. For example, small inaccuracies cannot cause disturbances by sliding of the inner end face of a sealing element, for example 66_2 , from the correlated disc 63₂ to an adjacent disc 63₁, or 63₃. Such a disturbing displacement of a sealing element is, for example, possible if a disc 66_2 is not accurately positioned and moves with the end face confronting disc 63₂ into the region of the disc 63₃, when the sealing region D of the respective two discs pass under the respective sealing element 66_2 . As noted above, in the region D, the outer contour of adjacent discs overlaps in circumferential direction and has the same radius of curvature.

FIGS. 22 and 23 show how the sealing elements 66 can be constructed to overcome this difficulty. In the proximity of the sealing inner end face 66a, two edges 66b are rounded off and tapered. These are the edges which may engage a wrong disc, considering the direction of rotation and the position of the rotor disc 63. If, for example, in the region D of the rotor disk 66₃ in FIG. 14 is in the uppermost position, that is directly under the sealing element 66₃, and if the rotor moves in the direction of the arrow Pf, the sealing element 66₃, if it projects a little to the right, could run onto the adjacent rotor disc 63₂ and be maintained by the same at least temporarily at such a height that it could not engage the rotor disc 63 with its inner end face to perform the necessary sealing function. The rounded-off and tapered edges 66b prevent this occurrence, because the sealing element 66₃ is not immediately radially lifted by the adjacent rotor disc 63₂, but pushed back in axial direction due to the effect of the tapered and rounded-off edge portions 66b, provided that the same are disposed in accordance with the direction of rotation of rotor R and the position of the associated rotor disc 63.

FIGS. 19 and 20 illustrate a further improvement according to the invention. It has been found in practical test runs, that the row or stack S_1 of sealing elements 66 is difficult to maintain in the desired cooperating position in relation to the conveyor screw discs 63. Thermal expansion and contraction take place in rotor R and shaft 64 which are different from corresponding expansion and contraction of housing 60 and row of sealing elements 66. Furthermore, due to mechanical stresses, small axial displacements of the rotor may occur. It is necessary to prevent that such relative axial displacement have not influence, or only a negligible influence on the necessary cooperation between sealing elements 66 and the correlated rotor disc 63 by which the sealing effect is maintained. In accordance with the invention, at least at one end, and as illustrated in FIG. 19 at both ends of the row of sealing elements 66, a compensating member 80 is mounted in housing portion 65. Each compensating member 80 has a convex surface 81

which slightly above the rotor R, abuts the inner face 82 of the respective wall of housing portion 65. The other face of each compensating member 80 is planar and abuts the first and last sealing element, respectively, while the inner ends 83 of the compensating members 80 abut the annular peripheral surface portions of shaft portions 84. As is best seen in FIG. 19, the entire stack of sealing elements S_1 between the compensating members 80, can easily follow axial displacements of the conveyor screw. In addition to a more accurate assembly, lesser requirements regarding accurate measurements of the parts, and lesser sensitivity to temperature differences, this construction also results in reduction of the friction between the sealing elements 66.

FIG. 19 further illustrates an improvement of the invention according to which the pressure chamber 67, which is connected to conduit 70 with the high pressure conduit portion at the end of the conveyor screw, is closed by a check valve 85. As a result, the pressure chamber 67 is closed and contains a constant volume of pressure medium, disregarding leakage losses. Since the volume of the pressure medium in pressure chamber 67 is constant, the radial outer movement of a sealing element 66, which displaces the liquid, produces a pressure which acts on another sealing element 66 to move the same inward toward the axis of the rotor into sealing contact with the conveyor screw. Only when leakage losses take place, check valve 85 permits the entry of the pressure medium into the pressure chamber 67. Consequently, the pressure medium in pressure chamber 67 has the effect of an automatic pressure cushion. An advantage of this arrangement is that the movements of the pressure medium in pressure chamber 67 have practically no influence on the transport of the liquid or other transported material by the conveyor screw from the inlet to the outlet of the housing.

As shown in FIG. 21, it is possible to connect several housing units each of which contains a pressure chamber, a row of sealing elements, and a conveyor screw. Parts corresponding to FIG. 21 to FIG. 19 are designated by the same reference numerals. The multiple arrangement according to FIG. 21 has the advantage that each row or stack of sealing elements S_1 is of a limited length. Furthermore, the pressure chambers can be supplied with a pressure medium having an intermediate pressure so that the sealing elements of the first unit are not subjected in the respective first pressure chamber to the high pressure produced in the last unit, avoiding unnecessary friction losses and wear of the parts. Furthermore, the embodiment of FIG. 21 permits the assembly of the apparatus of a plurality of identical units B, each of which includes a housing 70, a row of sealing elements S_1 , and if desired, two parallel rows of sealing elements S_1 and S_2 , and compensating members 80.

It should be noted that compensating members could be used which are not mounted for rocking movement as described with reference to FIG. 19. Any construction which obtains adaptation of the row of sealing elements S_1 in axial direction in relation to the conveyor screw consisting of disc 63, can be used. For example, compensating members may be spring-biased, but the rockable compensating members 80 have been found particularly reliable and easy to assemble.

Each unit B includes a conveyor screw 91 consisting of discs 63 and mounted between spacing sleeves on a shaft 64 having an end portion 64 in a bearing on the housing cover 92. The inlet 62 communicates with the working chamber of the first unit on the right as viewed in FIG. 21, and an outlet is provided at the left end of the housing at an angle of 90° to the inlet 62. At the joining points of the several housing portions 90, bearings for the rotor shaft may be provided. The conveyor screw 91 consisting of discs 63 can be manufactured by precision casting, but it is also possible to mount stacks 91 of rotor discs 63 on the inner shaft 64a, as shown in FIG. 21. FIG. 15 corresponds substantially to FIG. 20, but shows springs 71 as pressure means, while FIG. 20 has a widened pressure chamber 47d.

Instead of two rows of sealing elements 46a, 46b, as shown in FIGS. 6 and 8, three rows of sealing elements staggered to each other may be used. In such an arrangement not only the spaces between adjacent sealing elements of each row are covered by the staggered sealing element of the respective other row, but if the sealing elements are accordingly designed, openings L, shown in FIG. 18, can be covered whereby the sealing effect is improved, particularly when the conveyor screw of the rotor has a trapezoidal cross section. Sealing elements move in radial or in substantially radial direction in relation to the axis of rotor R, and the compensating members 80 also permit adaptation of the sealing elements 66 to the respective conveyor screw when the rotor shaft is slightly bent or deflected.

FIGS. 24 to 28 and 28a, illustrate embodiments of the invention which permit a greater volume or amount of conveyed or pumped material. A housing 100 has an inlet 101 and a pressure outlet 102 and supports two rotor shafts 112 with conveyor screws 103 which respectively operate in two cylindrical working chambers as shown in FIGS. 25 and 27. The two parallel rotor screws 103 are so disposed that the distance between the same remains the same during rotation. In the plane where the two conveyor screws 103 are spaced the smallest distance, a row of sealing elements 105 is positioned, whose ends are simultaneously engaged by the discs of the two conveyor screws 103, as shown in FIGS. 24 to 27.

A slot in a transverse guide wall guides the sealing elements 105 for reciprocating movement toward and away from the axes of the two rotors, as best seen in FIGS. 25 and 27. The distance A does not change or vary during rotation of the rotors so that the ends of sealing elements 105 remain in contact with the surfaces of the rotors 103. Therefore, each rotor 103 serves as a pressure means for pressing the sealing elements against the surface of the other rotor 103. Since the sealing elements in the embodiments of FIGS. 24 to 27 cannot separate from the conveyor screws 103, it is not necessary to provide stop means as shown at 51 in FIG. 7.

In FIGS. 24 to 28, each housing 104 has an outlet 102 and an inlet 101. The shafts 112 pass through stuffing boxes 114 in a wall of the housing, and have end portions mounted in roller bearings 115 and connected by gears. As shown in FIG. 24, gears 111 on shafts 112 mesh with an intermediate gear 113 so that shafts 112 rotate in the same direction of rotation. End walls 108 and 109 confine the conveyor screw 103 and the stack of sealing elements 105. In FIGS. 24 and 25, the conveyor screw is composed of discs, as explained above, which in the embodiment of FIG. 26 and FIG. 27, the conveyor screws 103 are helical.

In the embodiment of FIG. 28, the rotor shafts 112 are connected by a pair of gears 111a and rotate in opposite directions. Two rows of sealing elements 105b respectively cooperate with the conveyor screws 103, and have confronting inner ends located in a pressure chamber to which pressure fluid from the outlet 102 is supplied through a conduit 110. The pressure in the pressure chamber 107 urges the sealing elements 105b apart so that the respective inner ends of the same are in sealing contact with the respective conveyor screws.

In the embodiment of FIGS. 28a and 29, the sealing elements 105a have an integral resilient central portion 106, and have a total length slightly less than the distance between the surfaces of the conveyor screws 103 so that the sealing elements 105a are pretensioned and sealing contact between the ends of the sealing elements 105a and conveyor screws 103 is assured. An end wall corresponding to end wall 108 in FIG. 26, not shown in FIG. 28, closes the pressure chamber. The end walls 108 and 109 confine the rows of sealing elements 105, 105a, 105b in axial direction, but in the embodiment of FIG. 28 they also define the pressure chamber 107 as it communicates only through conduit 110 with the pressure outlet 102 of the apparatus. If necessary, a check valve can be placed in the conduit 110 so that the volume in pressure chamber 107 is maintained constant, and only leakage losses are replaced

through the check valve and conduit 110. When the check valve is provided, very little of the pumped liquid is required for the pressure chamber 107.

In the embodiment of FIGS. 24 and 25, in which the rotor shafts 12 are driven to rotate in the same direction, the conveyor screws 103 have turns in the same sense. In the embodiment of FIG. 28 in which the rotor shafts 112 rotate in opposite directions, the conveyor screws are designed to have turns in opposite sense so that the radial distance between the surfaces of the two rotors remain the same. The turns of the two oppositely rotating conveyor screws have the same gradient and length, but mirror symmetrical directions of the gradient.

It is advantageous to mount the gears 111a in the housing, as shown in FIG. 28, so that stuffing boxes 114, as shown in FIG. 24, where gears 111 and 113 are located outside of the housing, can be omitted. In the embodiments of FIGS. 24 and 26, the ball bearings 115 are located outside of the housing separated from the transported liquid by stuffing boxes 114. Other shaft ends are mounted in bearings 116, communicating with the transported liquid in the housing. This arrangement permits the lubrication of the ball bearings 115 independently of the transported material with suitable lubricating agents.

If it is desired to increase the conveying speed of the pumped material, the conveyor screws can be provided with multiple threads.

In the embodiment of FIG. 30, a housing 240 has at opposite ends inlet means 241 and 241a, and at its center, a pressure outlet 242. A rotor R is mounted in the housing and includes a shaft 244 one end of which is mounted in a bearing in the inlet 241, while the other end passes through a stuffing box 219a to a ball bearing, not shown. The worm screws 243 and 243a are symmetrical to a central plane of symmetry 250 passing through the outlet 242. The shaft portion between the conveyor screws 243 and 243a is supported in a bearing L. The conveyor screws 243 and 243a are threaded in opposite directions, and respectively cooperate with rows of sealing elements 216, which function as described with reference to the other embodiments. In the embodiment of FIG. 30, the axial pressures exerted by the transported fluid on the conveyor screws compensate each other. Evidently, it is possible to place an inlet at the center and two outlets at the ends of the housing. However, the embodiment of FIG. 30 has the advantage that the stuffing box 219a is provided in the region of the low-pressure inlet.

Due to the compensation of the axial forces, not only better load conditions of the rotor and its bearings is obtained, but also the seal between the conveyor screws 243, 243a and the sealing elements 216 is improved. Due to the balancing of the axial forces, the sealing elements 266 move more easily relative to each other, and since the axial displacements of the rotor are reduced due to the compensation of the axial forces, the cooperation between the sealing elements 216 and the conveyor screws is improved. It will be understood that a symmetrical arrangement for compensating axial forces may also be provided in other embodiments of the invention, for example in the embodiment of FIG. 21 in which a plurality of conveyor screws is provided.

An improvement of the function of the sealing elements 66, in FIG. 21, for example, is obtained when adjacent sealing elements consist of different materials which slide on each other with low friction. For example, one sealing element 66₁ may consist of a corrosion-resistant metal, such as V2A steel, and the adjacent sealing element 66₂ may consist of a synthetic material, such as Teflon, and sealing elements consisting of different material may alternate along the row of sealing elements. In addition to the reduced friction during movement of the sealing elements, generation of a series of electric voltages is prevented, which also eliminates corrosion effects.

The sealed conveyor apparatus according to the invention is comparatively simple and inexpensive to manufacture, particularly as compared with eccentric or double eccentric conveyor screws. The apparatus is suitable for transporting very

sensitive material, which must not be roughly handled, for example, nuts, beans, or grains. For such a material, it is not necessary to produce high pressure, since it is sufficient that the material is transported. A certain pressure is, however, necessary for raising the material a certain height.

The apparatus is also suitable for transporting liquids or semiliquid fluid material, such as sausage stuffing. Material may also contain solids, and the apparatus may be used for pumping waste water, fruits preserved in syrup, semiliquid mortar, plaster and cement. Particularly when liquids containing solids, or highly viscous semiliquid media such as cement or mortar have to be transported, it is advantageous to use in the respective pressure chambers, another pressure medium, such as water under pressure, when cement is transported. In such a situation, it is particularly advantageous to provide the check valve 85 at the inlet pressure chamber 67, which is otherwise closed. In such an arrangement, the amount of pressure medium required for pressure chamber 67 is independent of the transported material, and comparatively low.

Another advantage of the invention is the solid central mounting of the rotor, and the possibility to select materials for the parts of the apparatus which are suitable for specific conveyed substances. For example, the parts of the apparatus may be made of corrosion-resistant and temperature-resistant materials, and also wear-resistant materials.

Test have been shown that the apparatus works at high efficiency, and a viscous transported substance, such as syrup, can be transported at a rotary speed of 900 revolutions per minute. Transported substances having average viscosity permit rotary speeds of 1,400 revolutions per minute, and very thin substances even permit rotary speeds of 2,800 revolutions per minute. The apparatus is compactly built and obtains a continuous transport of great volume of the conveyed material. The movable parts can be easily assembled and disassembled for repair and service.

In order to resist corrosion, inert metal parts can be used when corroding substances are pumped by the apparatus.

A high rotary speeds and diagonal or great transported volumes, pumps with two or more conveyor screws, as shown in FIGS. 24 to 29, are advantageous since a forced control of the sealing elements 105 can be obtained by two conveyor screws and a separation of the sealing elements from the conveyor screws is avoided at high speeds.

It will be understood that each of the elements described above, or two or more together, may also find a useful application in other types of screw conveyor pumps differing from the types described above.

While the invention has been illustrated and described as embodied in a sealed conveying apparatus including a row of sealing elements in contact with a conveyor screw, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be protected by Letters Patent is set forth in the appended claims.

We claim:

1. Sealed conveying apparatus comprising, in combination, housing means formed with conduit means including inlet means, outlet means, and a working chamber between the same; rotor means including at least one rotor mounted for rotation about an axis in said housing means and including conveyor screw means in contact with the inner surface of said working chamber for transporting a fluid material from said inlet means to said outlet means, said conveyor screw means being composed of a plurality of disks angularly staggered

equal distances about said axis and being eccentric to the same so that portions of said disks form the surface of said conveyor screw means; sealing means including at least one row of sealing elements mounted in said housing means for independent movement toward and away from said axis and having a row of inner end faces located in said working chamber in contact with said disks, respectively, on a surface line along the length of said conveyor screw means; and pressure means in said housing means acting on the outer ends of said sealing elements to bias said sealing elements inward into sealing abutment with said conveyor screw means.

2. Sealed conveying apparatus comprising, in combination, housing means formed with conduit means including inlet

15 means, outlet means, and a working chamber between the same; rotor means including at least one rotor mounted for rotation about an axis in said housing means and including conveyor screw means in contact with the inner surface of said working chamber for transporting a fluid material from said inlet means to said outlet means; sealing means including at least one row of sealing elements mounted in said housing

20 means for independent movement toward and away from said axis and having a row of inner end faces located in said working chamber in contact with a surface line along the length of said conveyor screw means; pressure means in said housing means acting on the outer ends of said sealing elements to bias said sealing elements inward into sealing abutment with said conveyor screw means, said pressure means including a pressure chamber in which said outer ends of said sealing elements

25 are located, said pressure chamber being formed in said housing means and having an inlet opening communicating with said conduit means; and a check valve in said inlet opening so that fluid material can enter through the same to compensate for fluid losses.

3. Sealed conveying apparatus comprising, in combination, housing means formed with conduit means including inlet

means, outlet means, and a working chamber between the same; rotor means including at least one rotor mounted for rotation about an axis in said housing means and including

40 conveyor screw means in contact with the inner surface of said working chamber for transporting a fluid material from said inlet means to said outlet means; sealing means including at least one row of sealing elements mounted in said housing means for independent movement toward and away from said axis and having a row of inner end faces located in said working chamber in contact with a surface line along the length of said conveyor screw means; adjacent sealing elements being made of different materials adapted to slide on each other; and pressure means in said housing means acting on the outer

50 ends of said sealing elements to bias said sealing elements inward into sealing abutment with said conveyor screw means.

4. Sealed conveying apparatus comprising, in combination, housing means formed with conduit means including inlet

55 means, outlet means, and a working chamber between the same; rotor means including at least one rotor mounted for rotation about an axis in said housing means and including conveyor screw means in contact with the inner surface of said working chamber for transporting a fluid material from said inlet means to said outlet means; sealing means including at least one row of sealing elements mounted in said housing

60 means for independent movement toward and away from said axis and having a row of inner end faces located in said working chamber in contact with a surface line along the length of said conveyor screw means; and pressure means in said housing means acting on the outer ends of said sealing elements to bias said sealing elements inward into sealing abutment with said conveyor screw means, said pressure means including springs in said housing means acting on said outer ends of said

65 sealing elements.

5. Sealed conveying apparatus comprising, in combination, housing means formed with conduit means including inlet

means, outlet means, and two working chambers between the same; rotor means including two rotors having parallel axes and mounted for rotation in said housing means, each rotor in-

cluding conveyor screw means in contact with the inner surfaces of said working chambers, respectively, for transporting a fluid material from said inlet means to said outlet means; sealing means including two rows of sealing elements mounted in said housing means for independent movement toward and away from said axes and having rows of inner end faces located in said working chambers, respectively, in contact with surface lines along the lengths of said two conveyor screw means, respectively; and pressure means in said housing means acting on the outer ends of said sealing elements to bias said sealing elements inward into sealing abutment with said conveyor screw means.

6. Sealed conveying apparatus comprising, in combination, housing means formed with conduit means including inlet means, outlet means, and a working chamber between the same; rotor means including at least one rotor mounted in said housing means for rotation about one axis and having conveyor screw means in contact with the inner surface of said working chamber for transporting a fluid material from said inlet means to said outlet means through said working chamber; sealing means including at least one row of sealing elements laterally abutting each other and mounted in said housing means for free independent movement toward and away from said axis, said sealing elements having adjacent inner end faces located in said working chamber in continuous contact with a continuous surface line between the ends and along the length of said conveyor screw means so that said sealing elements are outwardly displaced during rotation of said conveyor screw means; and pressure means in said housing means acting on said outer ends of said sealing elements to bias all said sealing elements inward into sealing abutment of said inner end faces on said surface line of said conveyor screw means whereby said working chamber is sealed between said inlet means and outlet means.

7. Sealed conveying apparatus as claimed in claim 6 wherein said conveyor screw means has turns forming an angle with said axis; and wherein said surface line is perpendicular to said turns of said conveyor screw means.

8. Sealed conveying apparatus as claimed in claim 6 wherein said pressure means include springs in said housing means acting on said outer ends of said sealing elements.

9. Sealed conveying apparatus as claimed in claim 6 wherein said pressure means include a plurality of means for applying a greater pressure to sealing elements abutting said conveyor screw means at the end thereof adjacent said outlet means than sealing elements at the end thereof adjacent said inlet means.

10. Sealed conveying apparatus as claimed in claim 6 wherein said inner end faces of said sealing elements are rounded off in the direction of said surface line, and are curved to match the circumferential outline of said conveyor screw means in circumferential direction.

11. Sealed conveying apparatus as claimed in claim 6 wherein said sealing means include two adjacent rows of sealing elements; and wherein the sealing elements of each row are staggered in the direction of said surface line so that spaces between sealing elements of one row are covered by the sealing elements of the other row, respectively.

12. Sealed conveying apparatus as claimed in claim 6 wherein said conveyor screw means is composed of turns having a trapezoid cross section; and wherein said inner end faces of said sealing elements are trapezoidal and have surface portions matching said trapezoidal cross section.

13. Sealed conveying apparatus as claimed in claim 6 wherein said pressure means includes a pressure chamber in which said outer ends of said sealing elements are located, said pressure chamber being formed in said housing means and having an inlet opening communicating with said conduit means; and a check valve in said inlet opening so that fluid can enter through the same to compensate for fluid losses.

14. Sealed conveying apparatus as claimed in claim 6 wherein said conveyor screw means is composed of a plurality of disks angularly staggered equal angular distances about said

axis and being eccentric to the same so that peripheral surface portions of said disks form the surface of said conveyor screw means; wherein each of said sealing elements is a prismatic body having four longitudinal edges and a rectangular inner end face abutting one of said peripheral surface portions, respectively; and wherein at least one of said longitudinal edges is rounded off adjacent said rectangular inner end face for cooperation with the adjacent disk.

15. Sealed conveying apparatus as claimed in claim 6 wherein said conveyor screw means has multiple helical turns.

16. Sealed conveying apparatus as claimed in claim 6 wherein said rotor means includes a shaft and two conveyor screw means having opposite turns spaced along said shaft; wherein said inlet means have two inlets at the remote ends of said conveyor screw means; and wherein said outlet means is located between said conveyor screw means.

17. Sealed conveying apparatus as claimed in claim 6 wherein said conveyor screw means has helical turns spaced a predetermined axial pitch distance; and wherein the axial thickness of said sealing elements and inner end faces is substantially less than said pitch distance.

18. Sealed conveying apparatus as claimed in claim 17 wherein said sealing elements are thin plates slidingly abutting each other.

19. Sealed conveying apparatus as claimed in claim 6 wherein said pressure means include a pressure chamber formed in said housing and containing a fluid medium under pressure; and wherein said sealing elements have outer end faces located in said pressure chamber subjected to the pressure of said medium so that said sealing elements are urged toward said conveyor screw means.

20. Sealed conveying apparatus as claimed in claim 19 wherein said housing means include stop means located in said pressure chamber outside of said outer ends of said sealing elements for limiting outward movement of the same in a position in which said inner end faces abut the surface of said conveyor screw means.

21. Sealed conveying apparatus as claimed in claim 20 wherein said stop means include a U-shaped member extending along the length of said row of sealing elements and being formed with perforations; and wherein said pressure means include a pressure chamber containing a pressure medium acting on said outer ends of said sealing elements and flowing through said perforations.

22. Sealed conveying apparatus as claimed in claim 19 wherein said conduit means communicate with said pressure chamber so that the transported material is the same as said medium in said pressure chamber whereby said conveyor screw means produces the pressure in the same.

23. Sealed conveying apparatus as claimed in claim 22 wherein said pressure chamber is located in said conduit means between said working chamber and said outlet means so that the entire transported material flows through said pressure chamber.

24. Sealed conveying apparatus as claimed in claim 22 wherein said pressure chamber is closed and communicates with said outlet means, and adapted for movement of said medium therein.

25. Sealed conveying apparatus as claimed in claim 22 wherein said housing means includes at least one partitioning wall in said pressure chamber dividing the same into at least two pressure chamber portions; and wherein said conduit means include conduits connecting different portions of said conduit means having different pressures with said two pressure chamber portions, respectively, so that groups of said sealing elements are subjected to different pressures for sealing at low friction.

26. Sealed conveying apparatus as claimed in claim 6 wherein the sealing elements in the outlet region of said working chamber are less thick in the direction of said surface line than the sealing elements in the inlet region of said working chamber.

27. Sealed conveying apparatus as claimed in claim 26 wherein said row of sealing elements includes groups of sealing elements having the same thickness in said direction of said surface line.

28. Sealed conveying apparatus as claimed in claim 6 wherein said conveyor screw means is composed of a plurality of disks angularly staggered equal angular distances about said axis and being eccentric to the same so that peripheral surface portions of said disks form the surface of said conveyor screw means.

29. Sealed conveying apparatus as claimed in claim 28 wherein said working chamber has a cylindrical inner surface with a predetermined radius; and wherein the outermost parts of said peripheral surface portions of said disks are in sliding engagement with said inner surface and have said predetermined radius of curvature.

30. Sealed conveying apparatus as claimed in claim 6 wherein said rotor includes shaft portions at the ends of said conveyor screw means; and wherein said housing means includes bearings for rotatably supporting said shaft portions.

31. Sealed conveying apparatus as claimed in claim 30 wherein one of said bearings is located in the proximity of said inlet means; wherein one of said shaft portions passes through an opening in a wall of said housing means between said one bearing and said inlet means; and comprising a stuffing box in said opening.

32. Sealed conveying apparatus as claimed in claim 6 and comprising compensating end members movably mounted in said housing means at the ends of said row of sealing elements and abutting the same and the ends of said conveyor screw means for aligning said ends of said row and said ends of said conveyor screw means.

33. Sealed conveying apparatus as claimed in claim 32 wherein said conveyor screw means is composed of a plurality of disks angularly staggered equal angular distances about said axis and being eccentric to the same so that peripheral surface portions of said disks form the surface of said conveyor screw means, said peripheral surface portions being parallel to said axis; wherein said inner end faces of said sealing elements respectively abut said peripheral surface portions of said disks and have a matching shape; and wherein said compensating end members hold said sealing elements in positions aligned with the respective correlated peripheral surface portions, respectively.

34. Sealed conveying apparatus as claimed in claim 33 wherein said housing means include walls perpendicular to said axis; wherein each of said compensating end members had a convex back face abutting one of said walls, and a planar front face abutting a sealing element at the end of said row, and a disk at an end of said conveyor screw means.

35. Sealed conveying apparatus as claimed in claim 6 wherein said rotor includes a shaft and a plurality of conveyor screw means spaced along the same and being separated by shaft portions.

36. Sealed conveying apparatus as claimed in claim 35 wherein said housing means includes a plurality of housing units; wherein said sealing means include a plurality of rows of sealing elements cooperating with said conveyor screw means, respectively, and wherein each of said conveyor screw means and rows is located in one of said housing units.

37. Sealed conveying apparatus as claimed in claim 36 wherein each conveyor screw means is composed of a plurality of angularly staggered disks fixedly secured to said shaft; and comprising spacing sleeves on said shaft portions between said conveyor screw means.

38. Sealed conveying apparatus as claimed in claim 6

wherein said housing means includes two working chambers between said inlet means and said outlet means; wherein said rotor means include two rotors having parallel axes and conveyor screw means in contact with the inner surfaces of said two working chambers, respectively; wherein said sealing means include two rows of sealing elements having inner end faces located in said working chambers, respectively, in contact with surface lines along the lengths of said conveyor screw means, respectively.

5 39. Sealed conveying apparatus as claimed in claim 38 wherein said housing means include end walls located at the ends of said conveyor screw means and said rows of sealing elements for maintaining the latter in abutting positions.

10 40. Sealed conveying apparatus as claimed in claim 38 including gear means connecting said two rotors for rotation in the same direction, and located in said housing means.

15 41. Sealed conveying apparatus as claimed in claim 38 wherein said conveyor screw means have left hand and right hand turns, respectively, and including gear means connecting said two rotors for rotation in opposite directions.

20 42. Sealed conveying apparatus as claimed in claim 38 wherein each rotor has first and second shaft portions in the proximity of said inlet means and outlet means, respectively; comprising roller bearing means for said first shaft positions located outside of said housing means, and sealing means for sealing said first shaft portions in said housing means; and bearings for said second shaft portions located in said housing means in said conduit means.

30 43. Sealed conveying apparatus as claimed in claim 38 wherein said pressure means includes a pressure chamber between said working chambers in which said outer ends of said sealing elements are located, said pressure chamber containing a fluid medium under pressure for biasing said sealing elements toward the respective conveyor screw means.

35 44. Sealed conveying apparatus as claimed in claim 43 wherein said pressure chamber communicates with said conduit means in the region of said outlet means so that said fluid medium is under pressure.

40 45. Sealed conveying apparatus as claimed in claim 44 including a check valve between said conduit means and said pressure chamber.

45 46. Sealed conveying apparatus as claimed in claim 38 wherein said sealing elements of said two rows are integrally connected to each other, respectively, so that each conveyor screw means constitutes said pressure means for pressing said integrally connected sealing elements against the respective other conveyor screw means.

50 47. Sealed conveying apparatus as claimed in claim 46 comprising a buffer member between said outer ends of connected sealing elements and integrally connecting the same.

55 48. Sealed conveying apparatus as claimed in claim 47 wherein said buffer members are resilient; and wherein the distance between said two conveyor screw means is selected so that said buffer elements are resiliently pretensioned.

49. Sealed conveying apparatus as claimed in claim 6 wherein adjacent sealing elements are made of different materials adapted to slide smoothly on each other.

50 50. Sealed conveying apparatus as claimed in claim 49 wherein alternating sealing elements are made of metal and of a synthetic material, respectively.

51. Sealed conveying apparatus as claimed in claim 6 wherein said rotor is integral and cast.

52. Sealed conveying apparatus as claimed in claim 6 wherein said pressure means include a pressure chamber, and means for supplying a fluid medium under pressure to said pressure chamber.
